(57) **CLAIM**

We claim, the ornamental design for a device for producing three-dimensional articles, as shown and described.

DESCRIPTION

FIG. 1 is a front perspective view of a device for producing three-dimensional articles, showing our new design; FIG. 2 is another front perspective view thereof; FIG. 3 is a rear perspective view thereof; FIG. 4 is another rear perspective view thereof; and, FIG. 5 is a front elevation view thereof. The broken lines in the drawings depict unclaimed environmental subject matter.
